UNITED STATES PATENT OFFICE.

ALEXANDER B. SIMPSON, OF JERSEY CITY, NEW JERSEY

ELECTRICAL INSULATOR.

1,281,678.

specification of Letters Patent. Patented Oct. 15, 1916.

Original application filed April 21, 1914, Serial No. 833,454. Divided and this application filed May 6, 1916.
Serial No. 95,908.

To all whom it may concern:

Be it known that I, ALEXANDER B. SIMPSON, a citizen of the United States, and resident of Jersey City, in the county of Hudson and State of New Jersey, have invented certain new and useful Improvements in Electrical Insulators, of which the following is a specification.

The main object of my invention is to 10 simplify, cheapen, and expedite the means of insulating the joint interconnecting a plurality of wires in electrical contact.

In insulating the joints of electrical wires, the time required to wrap the insulating 15 tapes around the joint is very great, and the soiling of the hands and surrounding objects are often matters of serious expense.

My improvement consists in the peculiar 20 construction of a hollow tube insulator having a screw to clamp the insulation of the group of insulated wires which have been interconnected. In order that my invention may be fully understood, I shall first describe in detail the mode in which it is carried 25 into practice, and then distinctly claim the invention.

Reference is made to the accompanying 30 drawings forming part of this specification, in which like parts are designated by the same letters or numerals in all the figures.

Figure 1 is a sectional view of my insulator. Fig. 2 is a view of the same with a 35 group of wires. Fig. 3 is a view of the wire receiving end opening.

In Fig. 1, the insulator consists of the tube having one end closed up, designated by *b*, of porcelain, vulcanized fiber, or other hard insulation substance, and the screw of corresponding insulation substance, designated by letter *a*, is threaded and fits loosely 40 in the threaded hole designated by letter *o*, to form a space between the closed end of the tube and the screw, for the joint. To increase the scope of the clamping screw *a*, to follow any variation in the bulk of the 45 insulations to be clamped, the screw *a* is

made to screw into the body *b* as far as the radii center point line of the bore *N*, by continuing the threading of the opening *o* on the inner sides of the bore *N*, so as to 50 engage the threading of the screw *a* as far as the center point line of the bore *N*. On driving in or driving out the screw *a*, the wireway designated by *w*, is diminished or 55 enlarged at will.

The wires which are designated by 10, in Fig. 2, are shown insulated, and are interconnected at the joint designated by *c*, the joint being made by soldering, or clamping, after which the insulator is placed over the 60 joint *c*; by driving in the screw *a*, the insulation of the various wires are forced close together and tight against the wall of the tube, and clamped securely in position.

It is evident that the shape of the tube is 65 not confined to the form shown but may be square, or other shape, without departing from the boundaries of my invention.

I claim as my invention:

An insulator of hard insulating material, 70 consisting of a hollow tube having one end open and the other end completely closed up by an end wall, a threaded opening in the wall of the body close to the open end, and at right angles with and of the same diameter as the bore of the tube, the threading being continued through the wall on the inner surface of the bore, to a depth of half the diameter of the bore, a headless screw 75 of hard insulating material, having a flat tip, and a flat top, fitted loosely in the threaded opening, to clamp a group of wires between the screw tip and the inner surface of the tube.

In testimony whereof, I, ALEXANDER B. 80 SIMPSON have signed my name to this specification in the presence of two subscribing witnesses, this fourth day of May 1916.

ALEXANDER B. SIMPSON.
